AWNNG

Floyd D. Welch, Shreveport, La.

Application January 25, 1937, Serial No. 122,294

2 Claims. (Cl. 20—59)

This invention relates to awnings.

An object of the invention is the provision of a swingable frame in a support adjacent an opening in a building with the frame adapted to be swung to a plurality of predetermined positions outwardly of the building with a plurality of pivotally mounted slats adapted to be simultaneously operated to open or closed position and maintained in such positions.

Another object of the invention is the provision of an awning, including a swingable frame pivotally connected at one end to a support with means for moving the free end of the frame outwardly of the support, the means including a plurality of rotatable and slideable members with one of the members moving faster than the other.

A further object of the invention is the provision of an awning including a swingable frame having a plurality of slats pivotally connected at their ends with the frame and having the free longitudinal edges movable toward and away from the frame whereby said slats will be opened or closed, and movable latching means having a pivotal connection with a common connecting member with all of the slats, and including a plurality of notched links adapted to engage a keeper on the support.

A still further object of the invention is the provision of an awning including a plurality of pivotally mounted slats with each of the slats having the body portion formed of a non-metallic material and with a metal member reinforcing the free edges of the slats.

Another object of the invention is the provision of an awning including a plurality of slats pivotally mounted at their ends in a frame, each of the slats having a body portion formed of non-metallic material and reinforced at its edges by a metallic covering having an overlap adapted to engage over an adjacent slat.

This invention will be best understood from a consideration of the following detailed description, in view of the accompanying drawings forming a part of the specification; nevertheless, it is to be understood that the invention is not confined to the disclosure, being susceptible of such changes and modifications as define no material departure from the salient features of the invention as expressed in the appended claims.

In the drawings:

Figure 1 is a view in elevation of a window showing an awning constructed in accordance with the principles of my invention applied to a window.

Figure 2 is a vertical section taken along the line 2—2 of Fig. 1.

Figure 3 is a transverse section taken along the line 3—3 of Figure 2.

Figure 4 is a vertical section taken along the line 4—4 of Fig. 3.

Fig. 5 is a transverse section taken along the line 5—5 of Fig. 2.

Figure 6 is a vertical section through the operating means for the swingable frame of the 10 awning.

Figure 7 is a transverse vertical section taken along the line 7—7 of Fig. 6.

Figure 8 is a front view of a modified form of the awning applied to a window frame.

Figure 9 is a vertical section taken along the line 9—9 of Fig. 8.

Figures 10 to 18 inclusive are vertical sections showing various forms of the slats which may be employed in a swingable frame.

Figure 19 is a view in elevation of another form of my awning.

Figure 20 is a vertical section taken along the line 20—20 of Fig. 19.

Figure 21 is a horizontal section taken along the line 21—21 of Fig. 19.

Figure 22 is a fragmentary vertical section taken along the line 22—22 of Fig. 19.

Figure 23 is a fragmentary horizontal section taken along the line 23—23 of Fig. 19.

Figure 24 is a fragmentary vertical section taken along the line 24—24 of Fig. 23.

Referring more particularly to Figures 1 to 7 inclusive, 20 designates a window frame to which is hinged at 21 an awning frame 22. This frame 20 is hinged at the top bar 23 of the window frame 20 so that the lower end 24 of the frame is swingable outwardly from the window frame 22, which constitutes a support for the swingable frame 22.

This frame may be moved outwardly at its lower end from the window frame 20 by means of a rod 25 having a loose connection at 26 with the lower bar 24 of the frame 22. The rod 25 inwardly of the bar 24 is provided with fast threads, as shown at 27 and these threads engage a nut 28, secured to the inner face of a cylinder 29 so that when the cylinder is revolved the nut 28 will be revolved and cause the rod 25 and likewise the threaded portion 27 to move outwardly of the cylinder or sleeve 29.

The exterior surface of said sleeve is provided likewise with threads 30 which are adapted to be engaged by a nut 31 secured to the inner face of a sleeve 32 which is adapted to be rotated.

A crank 33 is secured at 34 to the sleeve 32.

and this crank is operated by a hand piece 35. The sleeve 32 is provided with an annular flange 36 embraced by a flange or collar 37 which is secured at 38 to the inner face of the window frame 20. It will be noted that the sleeve 32 passes through an opening 39 in said frame.

A plurality of slats 40 are pivotally connected as shown at 41, to the side walls of the frame 22, and at points which are intermediate the longitudinal edges of the slats and at the ends of said slats whereby the slats may be revolved on horizontal pivots within the frame 22.

The upper ends of all of the slats are pivotally connected as shown at 42 with a bar 43 which extends longitudinally of the frame 22, so that movement of the bar through the vertical will cause pivotal movement of the slats.

A linked latching device is shown more clearly in Figs. 2 and 4 and consist of a plurality of links 44 and 45. The link 45 is pivotally connected at 46 by means of a screw or bolt to the lower edge of slat 40b.

Each of the links is provided with a slot 47 adapted to receive a pin 48 extending laterally from a projection 49 on one end of the link 44. The inner end of the link 45 is bifurcated as shown at 50, to receive the projection 49. Each of the links 44, as shown at 51, is provided with notches adapted to engage a keeper 52 carried by the window frame 20. This keeper is in the form of a metal plate 53 secured at 53 to the window frame, and the central portion of the plate is punched out as shown at 55, to permit reciprocation of the links, and this opening is extended through the window frame, as shown at 56, and the connected links move through this opening or passage. The inwardly disposed links of the latching means extend downwardly and hang in this position when not in use.

The operation of the device shown in Figs. 1 to 7 inclusive is as follows: In Figure 2 the frame is shown in closed position, that is, in parallel relation with the window frame 20 with all of the slats likewise in closed position. At this time the latching device which includes the links 44 and 45 have a notch 51 of one of the links 44 in engagement with the keeper 52. The links 44 which are located within the window frame hang in a vertical position and a manipulating member 57 is connected with the lowermost link.

If it be desired to move the slats 40 to the dotted line position shown in Fig. 2, the links which extend outwardly of the frame are moved outwardly, thereby moving the upper edges of the slats downwardly to a substantially horizontal position, and all of the slats are moved simultaneously due to the fact that they are connected together by the vertical bar 43.

It will be appreciated that the slats 40 may be moved to any desired tilted position by the movement of the links in or out of the passage 56 in the frame 20, and the keeper 52 may then receive one of the notches 51 in one of the links 44 and maintain the slats in a predetermined position.

When, however, the swinging frame 22 is moved to the dotted line position shown in Fig. 2, or other position, the keeper 52 must be disengaged from the notch 51 in a link 44 to permit proper movement of the frame outwardly of the building. As soon as the frame has been swung to the desired position the slats may be adjusted by the linked latching means and then set in position, as previously explained.

The lower end of the frame is moved to the

desired position by rotating the crank 33 through the member 35. When the crank is rotated the outer sleeve 32 is revolved as will be the nut 31, and when the threads or lug 32a moves through the threads 30 of the sleeve or cylinder 29, said cylinder will be moved outwardly of the sleeve 32. When the sleeve 29 is moved outwardly it will likewise be revolved due to the action of the nut 31 so that the threads or a single lug 27a which is secured to the inner surface of the sleeve 29 will cause the rod 25 to be revolved and moved outwardly of the sleeve 29. Due to the fact however that the threads 27 have a higher pitch than the threads 30 of the sleeve 29, the rod 25 will be moved outwardly at a greater rate than the sleeve 29. Thus it will be seen that the lower end of the frame 22 will be moved out rapidly to a predetermined position by the proper rotation of the crank 33.

As was previously explained, it was necessary to release the link latching means from the keeper before rotating the crank and a release of the latching means of course will depend upon the extent of outward movement of the lower end of the frame 22. On the other hand, the crank 33 may be revolved with the latching means in engagement with the keeper 52 until the slats have been moved to the position desired. If it is desired to move the frame 22 outwardly to a greater extent than it would be possible with the latching means in engagement with the keeper 52, this latching means is released entirely and held by the hand of the operator until the frame is properly positioned, whence the latching means may be moved outwardly from the operator until the slats have been moved to a proper slanting position.

Referring more particularly to Figs. 8 and 9 it will be seen that a modified form of the device is employed in which the frame 60 is fixed in position at an angle to the vertical face of the wall of the building and maintained in this position by the proper supports.

A vane or slat 61 is also fixed in position to the side walls of the frame 60 while slats 40a are pivotally connected at 41a to the side walls of the frame. The upper end of the slats have pivotal connections with an operating bar 43 and this in turn is controlled by the linked latching means composed of the links 44 and 45 of different lengths and the operating handle 57. The link latching means is identical with the construction shown in Figs. 1 to 5 inclusive, and no further description need be given. A slat or valance 62 depends from the bottom bar 63 of the frame 60 at its lower edge and may be cut to provide the decorative design, as shown at 64.

The slats may be manufactured in various forms, as shown in Figs. 10 to 18 inclusive. All of the forms except that shown in Fig. 15 has a body portion 65 constructed of non-metallic material and a metal reinforcement or binding. The body portion is preferably made of insulating board.

Referring more particularly to Fig. 10, a body portion 65 is covered at one side with a sheet of metal 66 and the ends of the sheet are bent around the ends of the body portion 65 in U-shape formation with the free ends as shown at 67 counter-sunk into the body portion.

Figure 11 shows a slat having a body portion 65 formed of non-metallic material, but the outer surfaces of the slat are entirely covered by metal 68.

In Fig. 12 the edges of the U-shaped reinforce-

ing members 69 are pressed down firmly into the body portion 65. A cement may be employed to retain the reinforcing members in position and act as a seal.

5 In Fig. 13 the construction is similar to that shown in Fig. 10 except that the body portion 65 is cut away at its ends to provide a space 70 to receive a reinforcing rod 71 which embraces the periphery of the body portion with 10 this rod being enclosed by the U-shaped end portion 72 of the metal member 66. The slat shown in Fig. 13 may be employed as a master slat to which the link latching means may be connected because of the greater strength due 15 to the reinforcing peripheral bar 71. In those cases where it is desired to make the slats burglar-proof the type of slat with the reinforcing bar 71 may be used.

15 In Fig. 14 is shown another form in which the 20 U-shaped members 73 are applied to the ends of the body portion 65 of non-metallic material, and as distinguished from the form shown in Fig. 12, since the U-shaped reinforcing members are applied to three edges of the slat. The metal 25 members however in all of the various forms are generally applied to those edges where the pivots are employed.

25 In Fig. 15 is shown a slat formed entirely of metal and this slat has a body portion 74, side 30 flanges 75 and a longitudinal flange 76 at the reduced end of the slat, and a flange 77 projecting in the opposite direction from the flange 76 and adjacent the pivot point 78 of the slat. In this form the flanges 76 and 77 of adjacent slats 35 are in contact and cooperate to form a closed awning.

35 In Fig. 16 is shown another form in which the body portion 65 is covered by sheet metal 80, and this sheet metal is bent in U-shaped formation 40 as shown at 81 and 82 around the edges of the body portion. A lip 83 is constructed by bending the metal upon an extension of the sheet metal 80 so that the portion 83 forms an overlap on the adjacent slat and thereby provides a better seal.

45 Fig. 17 shows a slat formed of three-ply sections 84 to 86 inclusive. No metal is shown in this instance as reinforcing the edges. However, the metal may be employed if desired.

50 In Fig. 18 is shown a body portion 87 formed of beaver-board or any other composition of matter with the U-shaped reinforcing metal member 88 embracing one edge. Metal members however 55 may be applied to the ends of the slat where said ends are pivotally mounted in the frame of the awning.

55 In Figs. 19 to 24 inclusive is shown another modified form in which the slats are disposed vertically instead of horizontally, as shown in Figs. 1 and 8. The frame 90 may be either fixed in place 60 or it may be hinged at 91 to the frame of the window. The operating crank 93 and rod 25 are identical in construction to that shown in Figs. 6 and 7 and no further description is required.

65 The vertically disposed slats 91 are pivotally connected at 92 to the upper and lower bars 93 and 94 of the frame 90. The slats have an end, each pivotally connected at 95 with an operating bar 96 and a pivotal connection 97 on the slat 95a 70 also forms a pivotal connection for an operating

rod 98 which is connected with a link 99 of a linked latching means 100.

The links are provided with notches 101 adapted to engage a keeper 102 secured to the window frame 103. This frame has a passage 104 which aligns with an opening 105 in a plate 106 which carries the keeper 102 and which is inset in the frame 103 and secured to said frame by means of screws 107. This latching means need not be described, since it is substantially identical with 10 the latching means shown in the other forms and will therefore not only move the slats to a predetermined position but will hold said slats in said position.

The manipulating member 108 has a transverse pin 109 received by an inclined slot 110 in the end link 99 so that the member 108 may be readily removed from the link when desired. The links are likewise connected together by the transverse pins 111 which may be readily removed from the inclined slots 112, as has been previously explained. Shifting of the link latching means 100 in either direction moves the slats accordingly.

When the threaded member 29 has been moved 25 to its outer limit of the sleeve 32 the nut 31 will lock the members 29 and 32 so that continued rotation of these locked members will cause rapid outward movement of the threaded member 27 so that said member will move outwardly of the 30 sleeve 29 and extend the lower end of the frame 22 farther away from the bottom of the window frame due to the rotating nut 28 which is secured to the inner face of the member 29.

The blinds described herein are adapted to be 35 used as combination awnings and shutters.

The slats may be pivoted at the top edges thereof and have fusible links in the openers so that the slats would automatically close during a fire and cut off the draft. In this case all the materials employed would be fireproof.

The linked latching means may be connected to the upper or lower ends of the slats.

I claim:

1. In an awning, having a support and a swingable frame mounted on the support, a plurality of pivotally mounted slats in the frame, a bar having pivotal connections with the slats, a keeper on the support, a latching means connected with the bar and including a plurality of removably connected links, each link having a plurality of notches along the length thereof to engage the keeper, said latching means adapted to move the bar for opening and closing the slats.

2. In an awning having a frame and a plurality of pivotally mounted slats in the frame, a latching means composed of a plurality of links removably connected together for moving the slats to open or closed position, each link having a plurality of notches and a keeper on a support engageable with the notches for retaining the latching means and the slats in a predetermined position, each link at one end having a bifurcated portion and an angularly disposed slot located transversely of the bifurcated portion and at the other end a reduced portion received by the bifurcated portion of an adjacent link, and a pin received by the slots.
